UNITED STATES PATENT OFFICE.

FRANK S. OSBORN, OF EAST SHARON, ASSIGNOR TO HIMSELF, AND GEORGE M. CORWIN, OF SHINGLEHOUSE, PENNSYLVANIA.

REIN-HOLDER.

SPECIFICATION forming part of Letters Patent No. 320,277, dated June 16, 1885.

Application filed December 30, 1884. (No model.)

To all whom it may concern:

Be it known that I, FRANK S. OSBORN, of East Sharon, in the county of Potter and State of Pennsylvania, have invented a new and Improved Rein-Holder, of which the following is a full, clear, and exact description.

The object of my invention is to provide a new and improved rein-holder which is simple in construction, effective in use, and which 10 can easily be secured on a dash-board, &c.

The invention consists in the construction and arrangement of parts, as will be herein-after described and claimed.

Reference is to be had to the accompanying 15 drawings, forming part of this specification, in which similar letters of reference indicate corresponding parts in all the figures.

Figure 1 is a side view of my improved rein-holder secured on the side edge of a dash-board at the right-hand corner. Fig. 2 is a 20 sectional plan view of the same on the line $x-x$ in Fig. 1. Fig. 3 is a side view of a modified construction. Fig. 4 is a sectional plan view of the same on the line $y-y$, Fig. 3.

25 A metal frame, A, is provided at its top and bottom ends with jaws B, united by a rod, C, a short distance from the frame, and between the frame and the said rod a piece, D, of rubber is held, which projects some distance beyond the inner edge of the frame, the said inner projecting edge of the rubber being beveled.

The lower end of the frame is provided 30 with a forked piece, E, having two screws, F, of which one is passed over the edge of and the other through the dash-board G, as shown in Fig. 2, and then the screws are passed through a clamping-plate, I, on the outer surface of the dash-board. The nuts H are secured on the screws F, and thereby the frame 35 is clamped firmly on the dash-board. A hook, J, is formed on the upper end of the frame. The frame can also be held horizontally on the top and inner surface of the dash-board.

40 In the modification shown in Figs. 3 and 4 the frame A projects from a base-plate, K, which is secured on the end edge or top of the dash-board.

The construction shown in Figs. 3 and 4 is

to be applied on wooden dash-boards, whereas the construction shown in Figs. 1 and 2 is to 50 be used on leather and metal frame dash-boards. The two reins are passed between the edge of the dash-board and the rubber D, so that the reins extend from the inside of the vehicle over the edge of the rubber, over the 55 side edge of the dash-board, and then to the horse. The reins can easily be pulled in the direction from the horse without catching; but when the horse pulls or jerks on the reins they are brought against the edge of the rubber, and the friction produced on the edge of the rubber and the dash-board is so great as to catch and hold the reins and prevent the horse from pulling or throwing them from the dash-board. The hook J serves to hold the 60 buckle-frames of the reins when the reins are unbuckled.

The rein-holder is very simple in construction, safe and reliable, and can be attached very easily. The holder must always be on 70 the inside of the dash-board and at an inclination to the same.

The rubber D may be shifted between the frame A and the rod C, so as to project a greater or less distance from the said frame, 75 and thus leave a greater or less distance between the free edge of the rubber and the dash-board, thus adapting the holder to be adjusted for reins of different thicknesses.

Having thus described my invention, what I 80 claim as new, and desire to secure by Letters Patent, is—

In a rein-holder, the frame A, adapted to be secured to one edge of a dash-board, the said frame being inclined, as shown, and provided 85 with the jaws B, the rod C, connecting said jaws, and the rubber block D, secured behind the rod within the frame, whereby, when secured to a dash-board, as shown, the reins will be bent at or near a right angle between the 90 edge of the dasher and the edge of the block D, to insure a firm hold.

FRANK S. OSBORN.
